UNITED STATES PATENT OFFICE.

CLARENCE JANES, OF ONEIDA, NEW YORK.

PROJECTILE.

1,329,972.

Specification of Letters Patent. Patented Feb. 3, 1920.

Application filed June 3, 1919. Serial No. 301,393.

To all whom it may concern:

Be it known that I, CLARENCE JANES, citizen of the United States, residing at Oneida, in the county of Madison and State of New York, have invented new and useful Improvements in Projectiles, of which the following is a specification.

This invention relates to a projectile, and more particularly to a projectile in which the magazine is movable longitudinally with reference to the casing.

One object is to provide certain novel means for mounting the magazine within the casing, permitting the aforesaid longitudinal movement, upon impact, this longitudinal movement effecting the operation of the firing mechanism.

A still further object is to provide a magazine including a casing, a base portion, a nose portion, a plurality of rods extending longitudinally of the casing and between the latter and the magazine, said rods being mounted rigidly with reference to the base and with reference to the nose portion, and means projecting laterally from the magazines and slidably on the aforesaid rods, for guiding the magazine in its longitudinal movement.

A still further object is to provide, in connection with a structure of the type specified, a filling tube projecting from the magazine and slidable with reference to a filling bore formed in the base portion; and to provide resilient means for normally retaining the magazine in such position that the firing mechanism will be inoperative.

With the foregoing and other objects in view, the invention consists in the novel construction, combination, and arrangement of elements hereinafter described and claimed.

In the drawings—

Figure 1 is a view of the projectile partly in longitudinal section and partly in elevation,

Fig. 2 is a view chiefly in longitudinal section,

Fig. 3 is an end elevation,

Fig. 4 is a section on the line 4—4 of Fig. 1,

Fig. 5 is a section on the line 5—5 of Fig. 1,

Fig. 6 is a section on the line 6—6 of Fig. 2.

The cylindrical body portion of the projectile is designated 10, the base portion is

shown at 12, and the nose member is designated 14. The base portion is provided with a longitudinal bore slightly out of alignment with the longitudinal axis of the base and of the shell, this bore having communication with a recess 16 provided with undercut walls, the recess being closed by a slide 18. Movable longitudinally within the bore of the base is a filling tube 19 rigidly mounted in the magazine and projecting through one of the heads thereof. The tube is closed by any suitable plug or the like designated 20.

Within the forward portion of the casing is located a plate 25 provided with a central aperture through which a headed pin 27 passes, this pin having threaded connection with the apertured portion of the plate. The pin is therefore adjustable and may be spaced at the required distance from the firing pin. The pin first mentioned projects into an aperture 31 in the nose portion 14.

Extending between the base portion and the plate 25 are a number of rods 32, these rods being spaced apart at equal distances, and preferably four of these elements being employed, forming a cage-like construction. The rods are mounted rigidly at their opposite ends, respectively, in the base portion and in plate 25.

The magazine 35 carries laterally extending guiding elements 36 provided with central openings receiving the aforesaid rods 32. These guiding elements, in connection with the rods, serve to support the magazine within the casing and to permit of its longitudinal movement when impact takes place. Springs 37 surround certain of the rods and are located between the guiding elements 36 and the plate 25, the springs normally retaining the magazine in such position that the firing mechanism will be inoperative. When the magazine moves forward under impact, the springs will be compressed.

The rear end of the magazine is closed by a head 40 through which projects a rod 41 extending centrally of the magazine, and provided with a head 42 on the outer end thereof. The cap is received by the recessed portion of the rod 41, and is of course engaged by the firing pin 30 when impact takes place.

Mounted within the bore of the head 44 of the magazine is a spring engaged by the flanged portion 30' of the firing pin. A

sleeve 47 surrounds the boss 48 of the head last named and incloses the firing pin.

As previously intimated, the firing pin is operated when impact takes place and the 5 magazine moves forward, so that the firing pin is forced into positive contact with the pin 27 mounted in the plate 25.

What I claim is—

1. In a projectile, a body portion, a base 10 and a nose portion, a plurality of longitudinal guiding rods within the body and mounted in the base, forming a cage-like construction, and a magazine movable longitudinally between the guiding rods.
- 15 2. In a projectile, a body portion, a base, and a nose portion, a plurality of guiding rods extending through the body and spaced apart, forming a cage-like construction, a resiliently mounted magazine movable longitudinally between the guiding rods and firing means operative upon the longitudinal movement of the magazine against the action of the resilient elements of the mounting means.
- 20 25 3. In a projectile, a body portion, a base, and a nose portion, a magazine movable longitudinally through the body portion, a firing pin carried by the magazine, an element fixedly mounted with reference to the

nose portion, and means normally retaining 30 the magazine in position for holding the firing pin out of contact with the stationary element.

4. In a projectile, a body portion, a base, and a nose portion, a magazine movable 35 longitudinally within the body, a firing pin carried by the magazine, means normally retaining the magazine in a position spaced from the nose portion, but yielding under impact of the projectile, lateral guiding elements carried by the magazine, and stationary guiding rods coöperating with the guiding elements first named.

5. In a projectile, a body portion, a base, and a nose portion, a magazine movable 45 longitudinally within the body, guiding means for the magazine, firing mechanism carried by the magazine, resilient means controlling the position of the magazine and holding it in position retaining the firing 50 mechanism inoperative, a filling tube projecting through one end of the magazine, the base being provided with an aperture through which the tube passes, and means closing the entrance of the tube, said tube 55 being slidable with reference to the base.

In testimony whereof I affix my signature.
CLARENCE JANES.
